DESIGN FOR A TOILET SOAP RECEPTACLE OR SIMILAR ARTICLE

William C. Quinn, Reading, Mass.

Application March 27, 1945, Serial No. 118,727

Term of patent 14 years

(Cl. D4—3)

To all whom it may concern:

Be it known that I, William C. Quinn, a citizen of the United States, residing at Reading, in the county of Middlesex, in the Commonwealth of Massachusetts, have invented a new, original, and ornamental Design for a Toilet Soap Receptacle or similar article, of which the following is a specification, reference being had to the accompanying drawing, forming a part thereof, in which:

Figure 1 is a perspective view of a toilet soap receptacle embodying my new design. Figure 2 is a plan view thereof. Figure 3 is a longitudinal sectional view taken on the line 3—3 of Figure 2.

I claim:

The ornamental design for a toilet soap receptacle or similar article, substantially as shown.

WILLIAM C. QUINN.
